(57) **CLAIM**

The ornamental design for an anchor for holding an implantable medical lead or catheter, as shown and described.

DESCRIPTION

FIG. 1 is a top plan view drawing of the anchor for holding an implantable medical lead or catheter of our new design, the opposite side being a mirror image;

FIG. 2 is a top rear isometric view of FIG. 1;

FIG. 3 is a top front isometric view thereof;

FIG. 4 is an end view thereof, the opposite side being a mirror image;

FIG. 5 is a rear side view thereof; and,

FIG. 6 is a front side view.
